The ornamental design for the robotic mower wheels, as shown and described.

DESCRIPTION

FIG. 1 is a perspective view of robotic mower wheels in accordance with an embodiment of the present invention; FIG. 2 is a rear view of the robotic mower wheels of FIG. 1;

FIG. 3 is a front view of the robotic mower wheels of FIG. 1;

FIG. 4 is a right side view of the robotic mower wheels of FIG. 1;

FIG. 5 is a left side view of the robotic mower wheels of FIG. 1;

FIG. 6 is a top view of the robotic mower wheels of FIG. 1; and,

FIG. 7 is a bottom view of the robotic mower wheels of FIG. 1.

The broken line showing of a robotic mower in FIGS. 1-7 is included for the purpose of illustrating environmental subject matter only and the broken line showing of the tread pattern on the wheels is included for illustrating portions of the robotic mower wheels and forms no part of the claimed design.
